(57) **CLAIM**

I claim the ornamental design for a headlight of a three-wheeled vehicle, as shown and described.

DESCRIPTION

FIG. 1 is a front perspective view of a headlight of a three-wheeled vehicle showing my new design;

FIG. 2 is a right front perspective view thereof;

FIG. 3 is a left front perspective view thereof;

FIG. 4 is a right side view thereof; and,

FIG. 5 is a left side view thereof.

The portions of the three-wheeled vehicle shown in broken lines form no part of the claimed design.
